UNITED STATES PATENT OFFICE.

ELIZABETH M. M. DIMMERLING, OF BRADDOCK, PENNSYLVANIA.

COMBINED CHAIR AND CRADLE.

1,107,918.

Specification of Letters Patent. Patented Aug. 18, 1914.

Application filed January 23, 1914. Serial No. 813,882.

To all whom it may concern:

Be it known that I, ELIZABETH M. M. DIMMERLING, a citizen of the United States, residing at Braddock, in the county of Allegheny and State of Pennsylvania, have invented certain new and useful Improvements in a Combined Chair and Cradle, of which the following is a specification.

The present invention relates to an improved combined chair and cradle, and is designed especially to provide an article of furniture of this character that may be quickly, and with facility, converted from one use to the other when so desired.

The primary object of the invention is the provision of an article of furniture of this type which is comparatively cheap in cost of production, durable, easily and quickly convertible for its separate uses, and simple in its manipulations.

The invention consists essentially in certain combinations and arrangements of parts of the device by means of which it is adapted for use as desired, as will be hereinafter fully described.

In the accompanying drawings I have illustrated one complete example of the physical embodiment of my invention constructed according to the best mode I have so far devised for the practical application of the principles of the invention.

Figure 1 is a side elevation of the device in use as a baby's cradle. Fig. 2 is a side elevation, partly in section, on an enlarged scale, of the same device converted for use as a baby's high chair. Fig. 3 is a front elevation of the high chair. Fig. 4 is a side elevation of Fig. 3. Fig. 5 is a fragmentary view showing a portion of the chair seat and foot rest, in plan. Fig. 6 is a detail front view of Fig. 5. Fig. 7 is a detail showing the manner of detachably swinging the cradle from one of the cross bars. Fig. 8 is a section on line 1—1 of Fig. 9 through the extensible and telescopic members of the device. Fig. 9 is a side elevation of the telescoping extensible members. Fig. 10 shows an upright post or leg in cross section and the manner of hinging and holding up the hinged foot rest. Fig. 11 is another view detailing the foot rest. Fig. 12 is a detail view of the movable support for the foot rest, and Fig. 13 shows a portion of one of the posts in elevation with the foot-rest support jointed thereto.

In Fig. 1 the invention is embodied in a

baby's cradle which is supported from the four posts or uprights comprising the two short posts 1 and the two longer rear posts 2, the posts being more clearly indicated in Fig. 3. The front and rear pair of posts are connected by a pair of telescoping extensible members comprising the rod 4 fixed to the front post and the hollow bar 5 fixed to the rear post, and the front posts are connected by an upper and lower cross bar 6 and 7 with an intermediate bar 8, while the rear posts are connected by the upper and lower bars 9 and 10. The bars 6, 7, 8, 9 and 10 are all rigidly connected with their respective posts and form transverse brace bars for holding the parts or posts firmly braced, while diagonally arranged brace strips 11, 11 are fixed to the pairs of posts and the telescoping members 4 and 5. The device is movable and for this purpose is provided with casters 12 in the posts, as usual. The basket 13 which forms the cradle, is preferably of wicker-work, or ratan, and is formed with a fixed bottom 14, a foot board 15 which is slidable, and a sectional head board comprising members 16, and 17. In Fig. 1 it will be seen that the cradle is suspended by foot chains 18 and head chains 19 from the respective cross bars 6 and 9, and the cradle may swing or oscillate on these chains as usual. The chains are fixed to the cradle, but are detachable from the cross bars, by means of eyebolts 20 in the bars and spring hooks or clasp hooks 21 that are attached to the ends of the chains, thus providing an easily detachable suspending means.

In Fig. 2 which shows the device converted for use as a chair, it will be noted that a rod or wire 22 extends along the face of the bottom board 14, having its bent end 23 secured to the board, and its other end 24 passed through the board and secured at the outer side. This rod and a complementary one form guides for the slidable board 15 of the cradle, which is perforated, and adapts itself to be used as the seat of the chair. The seat is shown as resting on the top of the front or short posts at the front of the chair, and at the rear the seat is supported by a suitable number of pins 25 which are passed through perforations in the bottom board bored for this purpose. The portion 16 of the head board forms a tray for the high chair and the head portion 17 forms an extension of the back of the chair which is provided by the bottom board.

14, which is in effect a base board and should be so considered. The portion 17 of the head board is hinged to the base board and for this purpose I employ a suitable number 5 of metallic rings 26 which are located in adjacent perforations in the two boards and permit a swing of the board 17 with relation to the base board 14. The swing of the board 17 is guided and the movement steadyed by means of the curved arms 27 carried at each side of the board and movable through the cleats or brackets 28 fixed to the basket 13. The tray portion 16 is held in place, permanently, by the tongue and 15 groove strips 29 and 30, the former on the tray 16 and the latter on the basket 13, and the foot board which forms the chair seat is supported as shown and described. In Fig. 2 the basket is shown as supported by 20 a pair of lugs 32, 32 on the inner side of the hollow bar 5. A foot rest 33 is provided, and as this rest or board is foldable, it is hinged at 34 to the cross bar 8, and is supported by a movable lug 35 swiveled in the 25 brackets 36 fixed to the post 1, and movable from under the board when not to be used.

Having thus fully described my invention, what I claim is:

30 1. The combination in an article of furniture of a basket having a base board, an end board movable over the base board and

adapted as a seat, a second end board having a stationary portion and a hinged portion movable relatively thereto to give access to 35 the seat, and supporting post therefor.

2. The combination in an article of furniture having supporting posts, of a basket having a base board, an end board movable relative to the base board and means on said 40 base board for guiding the end board, means coacting with two of said posts for supporting the end board in its adjusted position, and a second end board having a stationary portion, and a movable portion hinged to 45 said base board, to give access to the adjusted end board.

3. The combination in an article of furniture having supporting posts, of a basket having a base board and guide rods thereon, a movable end board guided by said rods to adjusted position, pins in the base board coacting with a pair of said posts for supporting the end board in its adjusted position, and a second end board having a stationary portion, and a movable portion hinged to said base board, to give access to 50 the adjusted end board.

In testimony whereof I affix my signature in presence of two witnesses.

ELIZABETH M. M. DIMMERLING.
